ADJUSTABLE AIR REGISTER

Robert C. Vroom, Montclair, N. J., assignor to
Peabody Engineering Corporation, New York,
N. Y., a corporation of New York

Application January 30, 1939, Serial No. 253,610

12 Claims. (Cl. 158—1.5)

This invention relates to air registers or the like and more particularly to an air register for use in a burner for liquid, gaseous or pulverized fuel. Such a burner may, for example, 5 be of the general type disclosed in Peabody Patent No. 1,628,424, dated May 10, 1927, which shows an atomizer for liquid fuel having an atomizer tip adapted to produce a cone of atomized fuel in the burner throat. The operating capacity is varied by withdrawing a controlled portion of the fuel from the atomizer tip and returning the same to the fuel pump.

In a burner of this type, an air register is provided which may take the form of a casing having peripheral doors through which air for combustion is admitted. The doors control the direction and velocity of the air and cause the same to form a rotating mass of air within the air register having a degree of turbulence and 10 a velocity of rotation which are best adapted to promote the mixture of air and fuel. In this type of air register, it is desirable to provide means for controlling the quantity of air at different burner loads. This is accomplished in the 15 air register described in the patent to Peabody, above mentioned, by adjusting the angularity of the air doors or by varying the pressure in the plenum chamber around the air register. It has been found, however, that changing the angularity of the doors alters the velocity and the 20 turbulence of the rotating mass of air within the register and that varying the pressure in the plenum chamber changes the velocity of the air passing through the air doors, with a consequent change in efficiency of mixture and of 25 burner characteristics.

It is an object of the present invention to provide a novel and improved means for controlling the quantity of air supplied to the 30 burner without altering the other characteristics of the air supply.

Another object is to provide, in an air register of the type above indicated, means for varying the quantity of air supplied to the burner while 35 maintaining constant the direction, velocity and turbulence of the air within the register.

Another object is to provide a novel and improved air register of the type above indicated in which the air doors may be adjusted both 40 angularly and axially.

Another object is to provide an air register of the above type having novel and improved details of construction and characteristics of operation.

55 Various other objects and advantages will be

apparent as the nature of the invention is more fully disclosed.

Although the novel features which are believed to be characteristic of this invention are more particularly pointed out in the claims appended hereto, the invention may be better understood by referring to the following description, taken in connection with the accompanying drawings, in which certain specific embodiments thereof have been set forth for purposes of illustration.

In the drawings:

Fig. 1 is a longitudinal sectional view of a burner embodying the present invention;

Fig. 2 is a broken front elevation thereof;

Fig. 3 is a view similar to Fig. 1 illustrating a different embodiment of the invention;

Fig. 4 is a front elevation, partly in section, of the burner shown in Fig. 3; and

Fig. 5 is a partial sectional view illustrating a further embodiment of the invention.

Referring to the drawings more in detail, the invention is shown in Figs. 1 and 2 as applied to a burner for a furnace having a front wall 10 of the usual refractory material and an opening 11 in which is positioned a ring of refractory blocks 12 having flared inner surfaces 13 forming the burner throat. A plate 14, positioned over the front wall 10, may be provided with an opening 15 registering with the burner throat.

The burner is shown as comprising an air register having a front plate 18 secured, as by bolts 19, to a baffle 20 which is spaced from the plate 14 to form a plenum chamber 21 in which air is supplied under pressure to the register. A back plate 24 is secured to the front plate 18 by suitable means, such as stay bolts 25. The back plate 24 is flared, as at 26, to provide a discharge opening 27 registering with the opening 15 in the plate 14 and is provided with a flange 28 which is adapted to bear against the plate 14 for effecting an air seal. In certain

embodiments, such, for example, as an air register for use at atmospheric pressure, the register may be supported by securing the flange 28 to the plate 14, in which event the baffle 20 may be omitted.

The front plate 18 is shown as provided with a hub 34 in which a sleeve 35 is secured by suitable means such as a set screw 36. An atomizer barrel 37 having an atomizer tip 38 and a diffuser 39 may be mounted within the sleeve 35 and secured in position by a set screw 40. The tip 38 and diffuser 39 are arranged to direct a cone of finely divided fuel into the burner throat.

The atomizer barrel 37 may also carry a coupling member 41 containing the fuel connections, not shown.

The atomizer barrel may be of the type disclosed more in detail in the Peabody Patent 1,628,424, above mentioned, and may comprise, for example, means for supplying fuel under pressure to the atomizer tip and for discharging the same in a fine cone-shaped spray. The operating capacity may be varied by varying the supply pressure or by returning a portion of the fuel from the atomizer tip to the fuel pump and controlling the pressure in the return line, as more fully described in the said patent.

For controlling the supply of air to the burner, the register is provided with a plurality of peripherally spaced air doors 45 which are curved to form the peripheral wall of a substantially cylindrical air register chamber. Each door 45 comprises a section 46 provided with ears 47 which are pinned to a rod 48 journaled in the rear plate 24 and the front plate 18, and a section 49 having an ear 50 which is slidably held on the rod 48. The section 49 may be provided with a slot 51 engaged by a pin 52 carried by the section 46. The section 49 is similar in shape to the section 46 and is adapted to slide thereover in a direction axially of the register. A spring 53 may be carried on the rod 48 to normally hold the section 49 in its forward position. It is to be understood, of course, that the pin 52 may be positioned in the section 49 and the slot 51 may be formed in the section 46 if desired, or other securing means may be used. If sufficient support is obtained by the ear 50, the securing means between the sections 46 and 49 may be omitted.

Each rod 48 extends through the front plate 18 and carries a lug 55 having a slot 56 engaged by a pin 57. The pins 57 cooperating with the various lugs 55 are carried upon a ring 59 which is rotatably mounted on the front plate 18. Suitable means may be provided for operating the ring 59, such, for example, as a pinion 60 carried on a shaft 61 and engaging a rack 62 on said ring. The shaft 61 may be operated by suitable means, such as a handle 63. The arrangement is such that actuation of the ring 59 causes pivotal movement of the lugs 55 and swings the doors 45 about the rods 48 so as to adjust the openings between said doors. In certain instances individual adjusting means may be provided so as to permit individual adjustment of each door.

For controlling the axial position of the sections 49 of the air doors, a plate 70 is provided having a hub 71 slidably held on the sleeve 35. The plate 70 is of a diameter to engage the various air doors and to form with said doors and with the rear plate 24 an adjustable air chamber within the register. Axial adjustment of the plate 70 may be made by suitable means, such as by handles 72 attached to said plate 70 and extending through openings 73 in the front plate 18.

In the operation of this burner, the atomizer is set by suitable means for the required load and the air doors 45 are adjusted by means of the handle 63 to cause the air to enter the register with the desired direction and velocity to set up a whirling motion within the register adapted to produce an efficient mixture of air and fuel at the burner throat. Pressure in the plenum

chamber 21 may also be varied so as to effect the desired air flow.

When the load is reduced by suitable adjustment of the atomizer, the air flow through the register is also reduced by sliding the plate 70 axially of the register. In the embodiment shown this is accomplished by pushing the handles 72. It is to be understood, of course, that the handles may be threaded in the front plate 18 if desired, in which event, the axial adjustment of the plate 70 may be made by suitable rotation of the handles or any other convenient adjusting means may be employed.

Axial movement of the plate 70 causes the sections 49 of the air doors to slide over the sections 46, thereby varying the axial length of the air doors. In this way the effective axial section of the register is varied in accordance with the load so as to alter the quantity of air passing through the register without changing the condition of flow through the air doors.

It is to be understood that this invention is not restricted to a burner, but may be applied to air chambers, such as fan inlet boxes or the like and the term "air register" is intended to include such uses. Furthermore, the invention may be applied to burners of various types adapted for liquid, gaseous or pulverized fuel, which may be supplied to the burner throat either axially or peripherally, as shown, for example, in the U. S. Patents 1,671,494 to C. R. Stewart, dated May 29th, 1928, 1,790,395 to S. T. Warner, dated Jan. 27th, 1931 and 1,865,983 to S. T. Warner, dated July 5th, 1932. Furthermore, the gas may be supplied either axially or peripherally.

The invention is shown as applied to a burner operating under positive air pressure, which may be maintained in the plenum chamber 21 by suitable means, not shown. The register in this embodiment is supported by the baffle 20 which is provided with an aperture of sufficient size to permit the entire burner to be removed there-through. The invention may also be applied to a burner operating at atmospheric pressure, in which event the baffle 20, forming the plenum chamber, may be omitted and the air register may be mounted by securing flange 28 to the plate 14.

If, on adjusting the plate 70 in accordance with the combustion requirements, it is found that different conditions of air flow are required in order to maintain efficient operation, the air doors 45 may be readjusted angularly to produce the desired effect. The invention accordingly provides for independent axial and angular adjustment of the air doors.

In certain instances, it may be desirable to provide a single adjustment for both the angularity and the axial length of the air doors. One embodiment for accomplishing this is shown in Figs. 3 and 4 in which the parts corresponding to those of Figs. 1 and 2 have been given corresponding reference characters and a description thereof will not be repeated.

In this embodiment, the front plate 18 and the rear plate 24 are secured together by bolts 80 carrying spacing sleeves 81 on which the ears 47 and 50 of the air door sections 46 and 49 are journaled. Each of the air doors 46 is provided with a depending lug 83 having a slot 84 in which a pin 85 engages. Suitable securing means, such as a cotter pin or the like, may be provided for securing the pin 85 to the lug 83. The various pins 85 are mounted on a plate 86

having a hub 87 journalled for axial and rotary movement about the sleeve 35. The plate 86 is adjusted by suitable means, such as handles 88, extending through arcuate slots 89 in the front plate 18. The plate 86 may be rotatably adjusted simultaneously with the axial adjustment thereof by means of a pin 90 secured in the sleeve 35 and engaging a helical slot 91 in the hub 87.

In this embodiment, simultaneous axial and pivotal adjustment of the air doors 45 is obtained by pushing axially on the handles 88. Axial movement of the plate 86 causes adjustment of the axial length of the air doors 45 in the manner previously described. Axial movement of the hub 87 of the plate 86 causes the helical slot 91 to ride on the fixed pin 90 and to effect a predetermined rotary adjustment of the plate 86, thereby varying the angular position of the air doors 45. This rotary adjustment may be of a predetermined amount which is adapted to produce the desired condition of air flow within the register at various operating capacities. Individual adjustment of the angularity and of the axial length of the air doors may, however, be obtained by removing the pin 90, in which event independent pivotal movement of the plate 86 may be obtained by shifting the handles 88 circumferentially in the slots 89. In this way, any desired combination of adjustments may be obtained.

The invention accordingly provides for maintaining a constant air velocity throughout the entire capacity range of the burner. It is obvious also that the angularity of the air stream at any load may be changed without changing the velocity or the velocity may be changed without varying the angularity. In this way any conditions suitable for obtaining the maximum burner efficiency may be obtained at any operating load.

The embodiment shown in Fig. 5 is similar in general to the embodiment shown in Fig. 1. In this embodiment, however, the plate 100 is smaller in diameter than the peripheral ring of air doors and is adapted to slide under such air doors even when they are in full open position. The plate 100 is provided with a hub 101 which is slidable axially on the sleeve 35. The air doors 45 are, in this embodiment, each formed in one piece and are not axially adjustable inasmuch as it is not necessary to adjust the axial length thereof. The various air doors are shown as controlled by a ring 59 in a manner similar to that described in connection with Fig. 1.

In this embodiment, axial movement of the plate 100 varies the effective area of the air register, the plate forming a baffle which cuts off a portion of the interior of the air register from direct communication with the discharge opening.

This type of control may also be applied to a register having air doors arranged in the form of a frustum of a cone, such, for example, as shown in the Peabody Patent 1,628,424, above mentioned. In this embodiment the plate 100 may be used to control the operating capacity of the air register without changing the velocity of air flow through the air doors. It is to be understood that suitable locking means may be used for securing the various adjusting handles against unauthorized movement.

Although a specific embodiment of the invention has been shown for purposes of illustration, it is to be understood that the invention is capable of various uses and that changes and modifications may be made therein as will be

readily apparent to a person skilled in the art. Certain specific terms have been used herein merely for convenience of description and not as a limitation on the scope of the invention. The invention is to be limited only in accordance with the following claims.

What is claimed is:

1. In an air register, a set of peripheral air doors overlapping when closed to form the peripheral wall of an air register chamber, said doors being adjustable in length, means for adjusting the axial length of said doors and a baffle within said chamber adjustable with said doors for varying the axial length of said chamber whereby the air supply may be controlled while maintaining a substantially constant direction and velocity of flow within said chamber.

2. In an air register, a pair of end walls and a set of peripheral air doors cooperating therewith, said doors overlapping when closed to form the peripheral wall of an air register chamber and being adjustable both in length and angularly to control the flow of air to said chamber, means for adjusting one of said walls axially so as to vary the axial length of said chamber and means for effecting a corresponding adjustment in the axial length of said doors.

3. In an air register, a pair of end walls and a set of peripheral air doors cooperating therewith, said doors overlapping when closed to form the peripheral wall of an air register chamber and being adjustable both in length and angularly to control the flow of air to said chamber, one of said end walls being adjustable axially for varying the axial length of said chamber, and means for effecting a corresponding adjustment in the axial length of said doors.

4. The invention set forth in claim 3 in which the doors each comprise a plurality of sections which are relatively movable for adjusting the axial length of the door.

5. The invention set forth in claim 3 in which the doors are adjusted by axial movement of said one wall for adjustment therewith.

6. In an air register, a pair of end walls and a set of peripheral air doors cooperating therewith, said doors overlapping when closed to form the peripheral wall of an air register chamber and being adjustable both in length and angularly to control the flow of air to said chamber, one of said walls being adjustable axially for varying the axial length of said chamber, means for effecting a corresponding adjustment in the axial length of said doors, and independent means for effecting angular adjustment of said doors.

7. The invention set forth in claim 6 in which the doors are mounted on pivoted rods extending through said adjustable wall and mechanical linkage means is provided for angularly adjusting said rods in unison.

8. In an air register, a pair of end walls and a set of peripheral air doors cooperating therewith, said doors overlapping when closed to form the peripheral wall of an air register chamber and being adjustable angularly to control the flow of air to said chamber, one of said walls being mounted for axial and rotary movement, said doors each comprising axially overlapping sections which are adjustable for varying the axial length thereof, means controlled by axial movement of said one wall for adjusting the axial length of said doors and means controlled by rotary movement of said one wall for angularly adjusting said doors.

9. The invention set forth in claim 8 in which

means is provided for effecting rotary adjustment of said movable wall in response to axial movement thereof.

10. The invention set forth in claim 8 in which the movable wall is provided with a hub having a helical slot engaged by a stationary pin whereby axial movement of said wall effects simultaneous rotary adjustment thereof.

11. A burner comprising a fuel supply means adapted to produce a cone of finely divided fuel, and an air register for supplying air to said burner comprising a housing having a set of peripheral air doors overlapping when closed to form the peripheral wall of an air register chamber, said doors being adjustable both in length and angularly for controlling the flow of air to said chamber, and means for varying the effective axial length of said doors, whereby the air supply to said burner may be controlled while maintain-

ing substantially constant conditions of air flow in said register.

12. A burner comprising a fuel supply means adapted to produce a cone of finely divided fuel, and an air register for supplying air to said burner, comprising a pair of end walls and a set of peripheral air doors cooperating therewith, said doors overlapping when closed to form the peripheral wall of an air register chamber, means for adjusting said doors angularly to control the air flow therethrough, means for adjusting one of said walls axially so as to vary the axial length of said chamber and means for effecting a corresponding adjustment in the axial length of said doors, whereby the quantity of air supplied to said burner may be varied while maintaining constant conditions of air flow in said chamber.

ROBERT C. VROOM.
